Primary Examiner — Andrew Kerr(74) *Attorney, Agent, or Firm* — Buchalter; Cecily Anne O'Regan(57) **CLAIM**

The ornamental design for a brewing device, as shown and described.

DESCRIPTION

FIG. 1 is a top perspective view of a brewing device, showing my new design;

FIG. 2 is a bottom perspective view of the brewing device; FIG. 3 is a bottom perspective view the brewing device, shown in a condition of use;

FIG. 4 is a back view of the brewing device;

FIG. 5 is a left side view of the brewing device;

FIG. 6 is a right side view of the brewing device;

FIG. 7 is a top view of the brewing device; and,

FIG. 8 is a bottom view of the brewing device.

The broken lines in the drawings depict portions of the brewing device that form no part of the claimed design.
